(57) **CLAIM**

The ornamental design for a tee holder with magnetic ball mark retriever, as shown and described.

DESCRIPTION

FIG. 1 is a front perspective view of a tee holder with magnetic ball mark retriever showing my new design; FIG. 2 is a top plan view thereof;

FIG. 3 is a right-side elevation view thereof, the left-side elevation view being a mirror image thereof;

FIG. 4 is a bottom plan view thereof;

FIG. 5 is a front elevation view thereof;

FIG. 6 is a rear elevation view thereof;

FIG. 7 is front perspective view in use holding a golf tee; and,

FIG. 8 is a front perspective view in use retrieving a ball mark.

The broken lines in the drawings depict environmental subject matter and form no part of the claimed design.
